UNITED STATES PATENT OFFICE.

PHILANDER W. BATES, OF SILVER CREEK, NEW YORK.

LIFTING-JACK.

SPECIFICATION forming part of Letters Patent No. 242,863, dated June 14, 1881.

Application filed March 29, 1881. (No model.)

To all whom it may concern:

Be it known that I, PHILANDER W. BATES, of Silver Creek, in the county of Chautauqua and State of New York, have invented new and useful Improvements in Lifting-Jacks, of which the following is a specification, reference being had to the accompanying drawings.

This invention relates to that class of lifting-jacks which are provided with a lifting-cam, forming the short arm of the lifting-lever, a vertical lifting-bar which rests on the cam and is guided in the standard, and a head which is adjustable, connected with the lifting-bar and adapted to engage under the object to be lifted. The object of my invention is to improve the construction of the various parts which compose the lifting-jack; and my invention consists of the particular construction of these parts as hereinafter fully set forth.

In the accompanying drawings, Figure 1 is a sectional elevation, Fig. 2, a side elevation, and Fig. 3 a front elevation, of my improved lifting-jack. Fig. 4 is a horizontal section on an enlarged scale in line *x x*, Fig. 1. Fig. 5 is a vertical section on an enlarged scale in line *y y*, Fig. 1.

Like letters of reference refer to like parts in the several figures.

A represents the base of the standard; B, the center piece of the standard, secured by a tenon in the base A; and C C are the side pieces of the standard, which are bolted to the center piece, B, and rest on the base A.

D is the lifting-lever, pivoted between the side pieces, C, of the standard at *d*. The lever D is provided with a short arm, *d'*, which is formed like a cam, having a curved upper surface which gradually recedes from the fulcrum *d* of the lever, and which is provided at the end farthest from the fulcrum with a depression or notch, *d''*. The cam *d'* is preferably constructed of cast-iron and provided with a socket, *d³*, in which the hand-lever D is secured.

E is the lifting-bar, which is arranged in a vertical position between the upper portions of the side pieces, C, of the standard. The bar E is guided to move vertically in the standard by rollers *f*, which turn on arbors fixed in the standard and engage in vertical slots *g* formed in the bar E. The latter is provided at its lower end with a roller, *h*, whereby the bar E rests up-

on the upper surface of the cam *d'*. The pivot *d* of the lifting-lever D is arranged vertically below the bar E, as clearly shown in Fig. 1. The bar E is provided on its outer side with triangular teeth *i*, which have their abrupt faces turned upward and their inclined faces downward.

K represents the adjustable head which is applied to the lifting-bar E for engaging under the object to be lifted. The head K bears against the front edge of the bar E and is provided with two vertical ribs *l* which engage behind the rib I, on which the teeth *i* are formed, and whereby the head K is connected with the bar E, so as to slide vertically thereon. The head K is supported in any desired position by a pawl, *m*, which is pivoted in the head K, and projects from its lower side and rests upon the abrupt upper face of one of the teeth *i*. The head K is composed of two parts secured together side by side, by rivets or otherwise, and holding the pawl *m* between them. The pawl is attached to the head K by a rivet or pin which passes through an elongated opening, *n*, in the pawl, whereby the latter is rendered capable of a limited movement in the direction of its length within the head K. The overhanging upper end of the pawl is weighted, whereby the lower end of the pawl is turned against and kept in contact with the teeth *i* of the bar E. The pawl *m* is made so long that its upper end will come in contact with the top plate of the head K before the lower end of the slot *n* comes in contact with the pin passing through this slot. By this construction, the weight of the object resting on the head K is supported by the pawl *m* and the teeth of the lifting-bar E, and the pivot on which the pawl turns is relieved of this weight. The two halves of which the head K is composed are recessed on their contiguous sides to accommodate the pawl, and provided at their rear and lower sides with openings, through which the lower end of the pawl plays. One of the halves composing the head K is provided with a horizontal flange, *o*, which projects into the recess of the other half, immediately below its top rib, as shown in Fig. 5. The projecting flange *o* forms a bearing-surface against which the upper end of the pawl *m* works, and prevents the pawl from straining the upper joint of the two halves.

In raising the head K on the bar E the pawl

m slides over the teeth *i*, but upon applying a weight to the head *K* the pawl *m* engages with the teeth and firmly supports the weight. Upon disengaging the pawl from the teeth the head *K* is readily lowered on the bar *E*. By depressing the lever *D* the cam *d'* and the bar *E* resting thereon are raised until the extreme elevation of the bar *E* has been attained, when the roller *h* engages in the depression *d²* of the cam, and thereby locks the lifting-bar in this position as the pivot *d* of the lifting-lever is arranged vertically below the center of the roller. As the bar *E* is guided in the standard and supported upon the lifting-lever by rollers the bar is easily operated by the lever. The different parts of my improved lifting-jack are simple, strong, and easily put together, and form a very efficient and durable lifting apparatus.

20 I claim as my invention—

1. In a lifting-jack, the combination, with the standard provided with fixed rollers *f*, of the lifting-bar *E*, constructed with vertical slots *g* in which the rollers *f* engage, a head, *K*, made vertically adjustable on the bar *E*, and a lifting-lever *D*, having its fulcrum located vertically below the lifting-bar, and having its short arm formed by a cam, *d'*, provided near its farther end with a depression, *d²*, in which the lifting-

bar is locked when in its horizontal position, 30 substantially as set forth.

2. The combination, with the lifting-bar *E*, provided with teeth *i*, of the head *K*, and pawl *m*, whereby the head *K* is made adjustable on the lifting-bar, substantially as set forth.

3. The combination, with the lifting-bar *E*, provided with teeth *i*, of the head *K*, provided with a pawl, *m*, having a limited movement in the direction of its length within the head, whereby the thrust is applied to the end 40 of the pawl and the pivot thereof relieved from the strain, substantially as set forth.

4. The combination, with the lifting-bar *E*, provided with teeth *i*, of the head *K*, and the pawl *m*, having a slot, *n*, through which passes 45 the pivot by which the pawl is connected with the head *K*, substantially as set forth.

5. The combination, with the lifting-bar, of the head *K*, composed of two recessed parts secured together side by side, one of the parts 50 being provided with a horizontal flange, *o*, projecting into the recess of the other part, and a pawl, *m*, pivoted between the two parts of the head, substantially as set forth.

P. W. BATES.
